UNITED STATES PATENT OFFICE.

GEORGE H. SCHROETER, OF ST. LOUIS, MISSOURI.

COMBINED CIGAR CUTTER AND LIGHTER.

1,079,027.

Specification of Letters Patent.

Patented Nov. 18, 1913.

Application filed February 27, 1913. Serial No. 751,090.

To all whom it may concern:

Be it known that I, GEORGE H. SCHROETER, citizen of the United States, residing at St. Louis, State of Missouri, have invented certain new and useful Improvements in Combined Cigar Cutters and Lighters, of which the following is a full, clear, and exact description, reference being had to the accompanying drawings, forming a part hereof.

My invention has relation to improvements in combined cigar cutters and lighters; and it consists in the novel details of construction more fully set forth in the specification and pointed out in the claim.

In the drawings, Figure 1 is a front elevation of the device; Fig. 2 is a side view thereof; Fig. 3 is a rear elevation thereof; Fig. 4 is an enlarged view of the operating parts located within the casing, looking from the rear, the rear wall or slide being removed to expose said parts; Fig. 5 is a vertical transverse section on the line 5—5 of Fig. 4; Fig. 6 is a view similar to Fig. 4, with the burner-pipe removed; Fig. 7 is an enlarged middle transverse section through the valve-casing showing the feed-valve in normal position; Fig. 8 is a similar section showing the position of the valve after the cutter-lever has been depressed to actuate the cutter or blade; and Fig. 9 is a cross-sectional detail on the line 9—9 of Fig. 6.

The object of my invention is to construct a cigar-cutter the cutting blade of which shall control a valve which will automatically admit a current of gas or other fuel to a suitable burner with which coöperates a pilot flame rendered effective by the movement of the blade across the opening through which the cigar tip is inserted preparatory to the cutting action.

In detail the invention may be described as follows:—Referring to the drawings, C represents a casing or hood of any suitable design and provided with a rear sliding lid or gate 1 operating in suitable grooves or guide-ways *h* formed on the side walls of the casing, whereby access to the interior of the casing may be had at any time. The slide 1 is preferably provided with openings or perforations *o* for admitting air to the interior of the casing. The side walls of the casing are provided with ducts or flues 2 which likewise allow air to flow freely into the casing. Passed through the bot-

tom of the casing is a gas-supply pipe 3, which is maintained rigid within the casing by a cross-member or brace 4 engaging the side walls of the casing below the discharge ends of the flues 2, a screw 5 holding the pipe securely to the brace member. To the upper and inner screw-threaded terminal of the gas-pipe 3 is coupled a valve-casing 6, in which rotates a rock-valve 7, said valve being held against displacement by a terminal washer 8 passed over valve body and bearing against the casing wall, said washer being retained on the valve by a screw 9. The opposite end of the valve terminates in a pair of cross-arms 10, 10, by which the valve may be rocked with a throw of the blade or cutter as presently to be seen. To the upper end of the valve-casing is screwed the base of a Bunsen-tube 11 provided with a perforated screw-cap or gas-tip 12 for the delivery and free flow of the gas, said cap being positioned opposite the air passage-way 13 formed at the base of the Bunsen-tube as well understood in the art. The upper end of the Bunsen-tube terminates in a gas-burner 14 of any approved construction, and when the parts are assembled, the burner 14 comes directly opposite the central peripherally perforated hollow boss 15 formed in the dome or roof of the casing C. Leading from a convenient point of the valve-casing 6 is a wire tube 16 which is provided with a diminutive Bunsen-burner 17 secured in position in any mechanical manner, and directed toward the burner 14. This burner 17 serves to carry a pilot flame *w*.

Pivotedly mounted on the inner face of the front wall of the casing is a lever 18 one arm of which passes through a slot *s* in the side wall of the casing, the projecting end of said lever-arm being provided with a dished finger hold or bearing 19, the lever being normally held so as to maintain said outer arm in an elevated position by a contracting spring 20 one end of which is secured to the outer lever arm between the side wall of the casing and the axis of the lever, the opposite end of the spring being fastened to the front wall of the casing. Hinged to the free end of the inner lever arm is one end of a link 21 whose opposite end is pivotally coupled to the end of one arm of an oscillating valve-control lever 22 pivoted near its center to the front wall of the casing C. The lever 22 is provided with lugs or fork-mem-

bers 23, 23, arranged in pairs on opposite sides of the axis of rotation of the lever, each pair being adapted to engage an arm 10 of the valve 7. In this way the valve with its casing 6 are readily detachable from the lever 22, a decided advantage in assembling or disassembling the parts.

The valve 7 is provided with a main cross-port *a*, and supplemental ports *b*, *c*, (the port *b* being the smaller) communicating therewith on opposite sides. For a normal position of the valve the port *b* is so positioned as to conduct the gas from the pipe 3 to the port *a* which in turn conducts it (considerably expanded and reduced in pressure) through a constricted passage *e*, to a port *d* in the casing 6, the port *d* conveying the gas to the tube 16 and pilot-flame burner 17 where the gas burns with a tiny flame *w*.
When the valve 7 is rocked with the depression of the outer arm of the lever 18, the port *a* conducts the main current of gas to the burner 14, bringing the larger port *c* into communication with port *d* (Fig. 8) whereby an increased quantity of gas is delivered to the pilot-burner 17 which thus projects a long pilot-flame *w'* well up against the stream issuing from the burner 14, and igniting the latter. The end of the lever 22 opposite that to which the link 21 is attached carries a blade or cutter 24 bearing against the inner face of the front wall of the casing C, and sweeping across an opening O through which the tip of the cigar to be cut is inserted.

From the foregoing the operation will be readily understood. When the parts are at rest and in their normal position, the outer end of the main or actuating lever 18 is elevated, the blade 24 is to one side of the opening O and the valve-ports are as indicated in Fig. 7. By inserting the tip of the cigar into the opening O, and depressing the outer lever arm of the lever 18, the valve 7 is rocked so as to dispose the ports thereof as shown in Fig. 8. At the same time the lever 22 (which controls the valve 7) is oscillated in proper direction to swing the blade or cutter across the cigar and thus sever the

tip (see dotted position of the parts in Fig. 50). The severed tip drops to the bottom of the casing C. The cigar being cut, the smoker temporarily holds the lever 18 in its depressed position, the gas issuing from the burner 14 having been ignited by the elongated pilot-flame *w'* as a result of the increased quantity of gas delivered thereto with the rocking of the gas-valve 7 to the position as shown in Fig. 8, and from the flame of the main burner the smoker can 60 light his cigar. Upon releasing the lever 18, the spring 20 (which was under tension during the depression of the lever) restores the parts to their first or normal position to be actuated by the next smoker. The necessary complement of air is delivered to the burners not only through the flues 2, but through the perforations *o* of the slide 1.

Having described my invention, what I claim is:—

In a combined cigar cutter and lighter a casing or hood provided with air feeding means, and having an opening in the wall for the insertion of a cigar-tip, an actuating lever pivoted on the inner face of the wall 75 aforesaid, and having an arm projecting through the contiguous wall of the hood, a second lever mounted pivotally on the inner face of said wall, a blade on one arm of said lever sweeping across the opening aforesaid, 80 a link coupling the opposite arm of said blade-carrying lever to the adjacent arm of the actuating lever, a valve-casing opposite the blade-carrying lever, a spring for controlling the actuating lever, a rock-valve in 85 the valve-casing, a pair of arms carried by the rock-valve outside the valve-casing and disposed in diametrically opposite directions, and lugs disposed in pairs on opposite sides of the axis of oscillation of the blade-carrying lever for detachably engaging the arms on said rock-valve.

In testimony whereof I affix my signature, in presence of two witnesses.

GEORGE H. SCHROETER.
